ADJUSTABLE BUSHING FOR DRILL JIGS

Filed Aug. 25, 1945

INVENTOR.

Richard E. Maples

UNITED STATES PATENT OFFICE

2,497,679

ADJUSTABLE BUSHING FOR DRILL JIGS

Richard E. Maples, Lakeville, Mich.

Application August 25, 1945, Serial No. 612,622

8 Claims. (Cl. 77—62)

1

My invention relates to an adjustable guide bushing for drills, reamers, and so forth, for use in cases where a number of holes in a jig, or in a tool, machine or mechanism may be required to have a center distance or distances from one another or from some point or surface upon the work, all within very close tolerance limits. By the use of my said invention, work of this character may be accomplished without the use of slow and costly jig-boring machines of the well-known Swiss and similar types.

In carrying my invention into effect the various holes are laid out by ordinary workshop methods, such as by scribe and measuring instruments, and tentatively located with approximate accuracy, and at the centers so located holes are drilled and reamed to properly receive my improved bushings by which adjustments are made to meet very close limits as above stated.

In order that my invention, and the method of carrying it into effect, may be readily understood I will now describe an example of its use with reference to the accompanying drawings, in which—

Figure 1 is a plan view showing a simple form of jig having four holes, with a work-piece held therein.

Figure 2 is an end view of the same.

Figure 3 is a plan view of one of the bushings drawn to an enlarged scale.

Figure 4 is a transverse section of the same showing the arrangement of the component parts of the bushing.

Figure 5 is a plan view of the bushing taken in section on line 5—5 of Figure 4, showing the graduations for adjusting the same, and

Figure 6 is a section of the bushing similar to Figure 4 showing one method of securing the component parts of the bushing in place after final adjustment.

Like characters designate corresponding parts throughout the several views.

In the drawings, A is the body of the jig, having facings A₁ on two sides and having set screws A₂ opposed thereto, whereby the work-piece W may be securely clamped in position. It is assumed that four holes are to be drilled in the work-piece at the points marked H, H₁, H₂, and H₃, and at these points holes are bored in the jig considerably larger than the diameter of the main drill bushings B which they are to receive.

As shown in Figures 3, 4 and 5, the main bushing B is surrounded by a pair of auxiliary bushings C and D, arranged one within the other, each of the said bushings having eccentric bores.

2

In other words, the outer bushing C has its outside diameter a slip fit in the hole in the jig while its inside diameter, eccentric to the outside diameter, is such as to receive the outer diameter of the bushing D with a slip fit. The bushing D is also bored eccentrically to receive the main bushing B with a slip fit.

Thus, when the bushings are assembled as shown, and the eccentricity of the bushings C and D is one sixty-fourth inch in each case, a total variation in the position of the main bushing is obtained amounting to one-sixteenth inch by rotating the bushings C and D through 180 degrees.

To facilitate this adjustment the apices of eccentricity are marked with a dot as at d. Lines are also marked at points 180 degrees therefrom, and the upper face of the bushing D may have graduations G thereon as shown. Notches N are also provided to receive special wrenches for their accurate adjustment.

For example, when the apices are 180 degrees apart the main bushing is central with the hole bored in the jig, and if the apices are each moved through the same number of graduations but in opposite directions the center of the main bushing will be moved along a straight line passing through the original positions of the apices.

When therefore the only necessary correction of the bored holes is to be made along the line x—x in Figure 1, that is to say, in the distance between holes H and H₁, the apices are originally located upon this line. If, however, there is an equal error along the line y—y, the apices are placed on a line at 45 degrees, as indicated at z—z. In both these cases the apices are each moved through the same number of graduations to effect the desired correction. Where the error along the different lines varies, the angle of the line on which the apices are to be originally located may be easily computed as will be understood.

The cases in which measurement of the exact centers by instruments is necessary are extreme ones. For example, where a master work-piece or a template with exactly spaced holes is available all that is necessary is to rotate the eccentric bushings until a plug gauge inserted in the main bushing B will enter a hole in the master work-piece or template.

In Figure 6 of the drawings is shown one method of securing the bushings in place after final adjustment has been made. In this arrangement the main bushing B, having the usual flange B₁, is locked against rotation by the screw S, thread-

edly engaging the body A, the said screw having an enlarged head S1 which enters into an arcuate cavity B2 in the flange. The bushing C has a flange C1 fitting into a counterbore in the body A while the bushing D has a somewhat thinner flange D1 fitting into a counterbore in the bushing C, the two flanges being flush with the body as shown.

Now, after the final adjustments have been made, an arcuate counterbore common to the flange C1, D1 is bored centrally with the screw S and a washer W1 is arranged to engage this counterbore and is fixed in place by the shoulder S2 on the screw S, which shoulder is in alignment with the upper surface of the body A.

While my improved method of adjustment has hitherto been described as applied to a jig bushing, it will be obvious that the same may be adapted with equal facility and advantage to the bearings of fine machinery and precision instruments.

Having thus described my said invention, what I claim and desire to secure by Letters Patent of the United States is:

1. The combination, with a support having a counterbored circular opening and a cylindrical element to be positioned therein, there being a space intermediate said bore and said element, of a pair of eccentric bushings telescoped one within the other in said space, said bushings each having flanges, outer surfaces whereof lie in a common plane substantially flush with a surface of said support, the outer bushing being a slip fit in said opening and bored eccentrically to receive the inner bushing, and the inner bushing bored eccentrically to receive said element, whereby said element may be accurately located, there being means for locking said bushings in adjusted position relative to said support, said means comprising a counterbore in the face of said support, said bushing flanges having aligned recess forming extensions of said counterbore to provide a locking recess, a locking member fitting in said locking recess, and means holding said locking member within said locking recess.

2. In a fixture, a support having an aperture therein, a first member having a portion positioned within said aperture, said first member having an aperture therein eccentrically positioned with respect to the peripheral surface of said portion, a second member having a portion positioned within said first member aperture, said first and said second members being arranged to be rotated relative to each other and to said support, said members and said support having recesses therein which when said members and said support are in the desired relative positions form a desired pattern, and a locking member substantially conforming in size and shape with said pattern and positioned in said recesses for holding said first and second members and said support against relative rotation.

3. In a fixture, a support having an aperture therein, a first member having a portion positioned within said aperture, said first member having an aperture therein eccentrically positioned with respect to the peripheral surface of said portion, a second member having a portion positioned within said first member aperture, said first and said second members being arranged to be rotated relative to each other and to said support, said members and said support having recesses therein which when said members and said support are in the desired relative positions are in alignment, a locking member sub-

stantially conforming in size and shape with said recess and positioned in said aligned recesses for holding said first and second members and said support against relative rotation, and means for holding said locking member in said recesses.

4. In a fixture, a support having an aperture therein, a first member having a portion positioned within said aperture, said first member having an aperture therein eccentrically positioned with respect to the peripheral surface of said portion, a second member having a portion positioned within said first member aperture, said first and said second members being arranged to be rotated relative to each other and to said support, said members and said support having recesses therein which when said members and said support are in the desired relative positions align to provide a cylindrical recess, and a cylindrical member of substantially the same size as said aligned recesses and positioned within said cylindrical recess whereby said members and said support are held against relative rotation.

5. In a fixture, a support having a cylindrical aperture therein, a first member having a cylindrical portion positioned within and substantially fitting said aperture, said first member having a cylindrical aperture therein positioned eccentrically with respect to said cylindrical portion, a second member having a cylindrical portion positioned within and substantially fitting said first member aperture, said second member having positioning means located eccentrically to said second member cylindrical portion, said members having recesses which when said members are in adjusted positions are aligned, and means carried by said support and engageable with both of said members and positioned within said aligned recesses for locking both of said members against rotation relative to each other and to said support.

6. In a fixture, a plate-like supporting member having a cylindrical aperture opening through one face thereof, said aperture having an enlarged diameter portion opening through said face, a first cylindrical member having a peripheral outwardly extending flange adjacent one end thereof and positioned within said aperture with said flange in said enlarged diameter portion, said first member having a cylindrical aperture opening through the end face of said first member adjacent said one end and having an enlarged diameter portion opening outwardly through said end face, said first member aperture being eccentrically arranged relative to the cylindrical side wall of said first member, a second cylindrical member having a peripheral outwardly extending flange adjacent one end portion thereof and positioned within said first member aperture with said second member flange in said second member enlarged diameter portion, said flanges and said supporting member being provided with cutaway portions which when said members are selectively positioned as desired form a recess of predetermined contour and size, and means of said predetermined contour and size received within said recess for holding said members and said support against relative rotation.

7. In a fixture, a platelike supporting member having a cylindrical aperture opening through one face thereof, said aperture having an enlarged diameter portion opening through said face, a first cylindrical member having a peripheral outwardly extending flange adjacent one end thereof and positioned within said aperture with

said flange in said enlarged diameter portion and an outer surface of said flange coplanar with said face, said first member having a counterbored cylindrical aperture opening through the end face of said first member adjacent said one end, said first member aperture being eccentrically arranged relative to the cylindrical side wall of said first member, a second cylindrical member having a peripheral outwardly extending flange adjacent one end portion thereof and received within the counterbore of said first member aperture, said second member flange having an outer surface coplanar with said face, said supporting member having a second aperture adjacent to but externally of said supporting member aperture, said supporting member second aperture having a counterbore, said flanges having aligned recesses forming extensions of said last-named counterbore to provide a locking recess, and a locking element of substantially the same contour as said locking recess and fitting within said locking recess. 5 10 15 20

8. In a fixture, a platelike supporting member having a cylindrical aperture opening through one face thereof, said aperture having an enlarged diameter portion opening through said face, a first cylindrical member having a peripheral outwardly extending flange adjacent one end thereof and positioned within said aperture with said flange in said enlarged diameter portion, said first member having a cylindrical aperture opening through the end face of said first member adjacent said one end and having an enlarged diameter portion opening outwardly through said end face, said first member aperture being eccentrically arranged relative to the cylindrical side wall of said first member, a second cylindrical member having a peripheral outwardly extending flange adjacent one end por-

tion thereof and positioned within said first member aperture with said second member flange in said second member enlarged diameter portion, said supporting member having a second aperture adjacent to but externally of said supporting member aperture and internally threaded, said supporting member having a counterbore concentrically with said member second last-named aperture, said flanges having aligned recesses forming extensions of said counterbore to provide a circular locking recess, and a circular locking member positioned in said locking recess.
